UNITED STATES PATENT OFFICE.

WILLIAM H. BLOOD, JR., OF BOSTON, MASSACHUSETTS.

DESIGN FOR A COLLAPSIBLE TUBE.

No. 38,579.

Specification for Design.

Patented May 21, 1907.

Application filed January 26, 1907. Serial No. 354,309. Term of patent 3½ years.

To all whom it may concern:

Be it known that I, WILLIAM H. BLOOD, Jr., a citizen of the United States, residing at Boston, in the county of Suffolk and State of Massachusetts, have invented a certain new, original, and ornamental Design for Collapsible Tubes, of which the following is a specification, reference being had to the accompanying drawing, forming a part thereof.

The figure is a plan view of a collapsible tube, showing my design.

I claim:

The ornamental design for a collapsible tube, as shown.

W. H. BLOOD, JR.
